FOOTWEAR

Curry Ora Walper, Kitchener, Ontario, Canada

Application July 9, 1943, Serial No. 494,095

8 Claims. (Cl. 36—70)

This invention relates to improvements in the heels of footwear of the character disclosed in my Patent No. 2,331,062 dated October 15, 1943, and in my co-pending application Serial No. 486,358, filed May 10, 1943.

In the first identified or original structure the sides of the tongue merged to a point located beneath the shank portion of the footwear roughly on the median line, while in the second previous structure, which was designed more specifically for footwear for the requirements of persons having the abnormality or habit of excessively toeing out and after lifting their feet from the ground tilting them in such a manner that the inside edge of the heel and the projecting tongue fell considerably lower than the outside edge, the tongue was reshaped to remove the tip from its former median position to one substantially forward of the inner corner of the breast of the heel and also by deflecting the plane of the tongue inwardly and downwardly.

It has now been found, however, that considering those persons who tilt their feet laterally and toe out when walking, and even in many other instances, the tongue may be dispensed with entirely and the tread portion of the heel peculiarly shaped to balance the absence of the tongue.

The principal object of the present invention, therefore, is to provide a heel having a certain malformed or irregular tread portion, or more particularly the bottom surface thereof for the purpose of economically compensating the absence of the tongue which was common to the structures in both of the previous disclosures.

A second important object is to provide means for balancing the malformed or irregular heel tread portion during the act of walking.

A third important object is to provide combiningly with the malformed or irregular heel tread and compensation means a tongue in certain instances where one as well is desirable.

Still another important object is to provide a device of the kind specified which will be simple, effective, and inexpensive to produce and purchase.

With the above and other objects in view as will be hereinafter apparent, the invention consists in general of certain novel details of construction and combinations of parts hereinafter fully described, illustrated in the accompanying drawing and specifically claimed.

In the accompanying drawing like characters of reference indicate like parts in the several views, and:

Figure 1 is a side elevation of a heel constructed 55

in accordance with the present invention showing the inside or right side of the heel of an article of footwear for wear on the left foot.

Figure 2 is an opposite side view of the structure shown in Figure 1.

Figure 3 is a rear view of the structure as shown in Figures 1 and 2.

Figure 4 is a front elevation of the same.

Figure 5 is a bottom view of the heel.

10 Figure 6 is a side elevation showing a modified form of the present invention.

Figure 7 is a view similar to Figure 3 as with the heel solidly on the ground.

15 Figure 8 is a side elevation similar to Figure 1 modified by a tongue.

In the drawing 10 indicates the heel including the tread portion of the heel of a left article of footwear here shown typically in the form of that impervious protective covering for shoes commonly known as rubbers or galoshes. The shank portion of the footwear is indicated by the numeral 11, and it will be understood while the heel here shown is for the left foot, the parts hereinafter described are applicable to the like article as worn on the right foot and which with the left forms a pair, but will obviously occur in reverse arrangement.

In the second previously mentioned application 20 the tongue which extended forwardly from the base portion of the breast of the heel was described as being twisted to form a downwardly and inwardly directed declivity, the bottom of the tongue being substantially even with the corresponding surface of the heel tread, and the point or tip of the tongue lying roughly forward of the inner corner of the breast of the heel. The tip of the tongue was therefore the common destination of the water adhering to the various surfaces of the heel and from which it was cast or kicked in line with the path of the forward movement of the foot.

It has developed, however, that in many instances the tongue and also the ledge typical of both former disclosures may be entirely eliminated, and the tread portion of the heel instead malformed or misshaped to provide a combined inwardly and forwardly directed declivity 12 in the bottom of the tread portion as will be clearly discernable by reference to Figures 1, 2 and 3. Such heel tread formation or perhaps more properly speaking, malformation of the heel tread, will be observed to substantially correspond in general to the bottom surface of the twisted or similar formation of the tongue as it is described in the second previous application.

It will be noted that the inwardly and downwardly directed declivity 12 of the heel tread together establish a point or tip 13 to the heel and which fall on a plane very substantially lower than any other portion of the heel. This tip 13 in purpose and in use corresponds to the tongue tip in the structure described in the second previous application. The point 13 is therefore the common destination of the water molecularly adhering to the various surfaces of the heel when it is raised from wet paths or puddles similarly as is the tip of the tongue in both previous disclosures.

In order that when the heel is put to the ground under the weight of the wearer the foot will not be thrown out of normal vertical posture, the thickness of the sloping portion of the tread is preferably built down by a pie-cut shaped layer 14 which is formed of relatively elastic compressible material, but nevertheless wear-resisting, which is squeezed up against the more solid or relatively resistible material when under load and which elastically re-expands to normal thickness on the shifting of the load to the opposite foot during the act of walking.

In some instances it may be found preferable to build down the heel by means of an elastic pie-cut wedge 15, according to Figure 6, rather than by means of the similarly shaped layer 14, so that the entire heel tread surface will be characteristically homogeneous. Usually this layer or the wedge will be necessary to promote comfort to the wearer in walking by affording a substantially level engagement of the heel with the walked on surface. However, in the case of persons having the abnormality of toeing out and inclining their feet and hence very often even putting them to the walked on surface in a tilted position, the layer or wedge can be conveniently dispensed with without causing discomfort.

In Figure 8 is shown a heel similarly constructed with a declivitous layer and combined with a tongue 18. In such instances where a tongue is essential or desirable, the sloping plane of the heel tread at the breast line of the heel imparts to the tongue a more pronounced inwardly and downwardly directed declivity on both its surfaces in order that the general trend of the heel tread formation is carried throughout the tongue.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

I claim:

1. In a heel for an article of footwear and including a heel tread portion, said portion having in its tread surface a malformation consisting of an inwardly and forwardly directed declivity formed by building down said portion toward the inner forward heel corner, whereby a water-casting tip is formed in conjunction with said surface at said corner at a lower level than the remainder of said surface, the built down portion of the heel tread portion being formed by means of a layer of elastically compressible material.

2. In a heel for an article of footwear and in-

cluding a heel tread portion, said portion having in its tread surface a malformation consisting of an inwardly and forwardly directed declivity formed by building down said portion toward the inner forward heel corner, whereby a water-casting tip is formed in conjunction with said surface at said corner at a lower level than the remainder of said surface, the built down portion of the heel tread portion being formed by means of an inserted wedge of elastically compressible material.

3. In a heel for an article of footwear including a heel tread portion, said portion being formed with a gradual inwardly and forwardly directed normal declivity whereby a lower level water casting tip is formed at the inner forward corner of the heel, the declined tread portion being adapted to compress to a relatively more level position under the weight of the wearer of the footwear and to elastically expand to its normal form on suspension of the weight.

4. In a heel for an article of footwear including a heel tread portion, said portion being formed with a gradual inwardly and forwardly directed normal declivity whereby a lower level water casting tip is formed at the inner forward corner of the heel, the declined tread portion being adapted to compress to a relatively more level position under the weight of the wearer of the footwear and to expand to its normal form on suspension of the weight.

5. In a heel for an article of footwear including a heel tread portion, said portion being formed with a gradual inwardly and forwardly directed normal declivity whereby a lower level water casting tip is formed at the inner forward corner of the heel, the declined tread portion being adapted to deform to a relatively more level position under the weight of the wearer of the footwear and to elastically return to its normal form on suspension of the weight.

6. In a heel for an article of footwear including a heel tread portion, said portion being formed with a gradual inwardly and forwardly directed normal declivity whereby a lower level water casting tip is formed at the inner forward corner of the heel, the declined tread portion being adapted to deform to a relatively more level position under the weight of the wearer of the footwear and to return to its normal form on suspension of the weight.

7. In a heel for an article of footwear, said heel having a tread member, the member being formed with a gradual inwardly and forwardly directed normal declivity whereby a low level water casting tip is formed at the inner forward corner of said member, the declined member being adapted to deform to a relatively more level position under the weight of the wearer of the footwear and to elastically return to its normal form on suspension of the weight.

8. In a heel for an article of footwear, said heel having a tread member, the member being formed with a gradual inwardly and forwardly directed normal declivity whereby a low level water casting tip is formed at the inner forward corner of said member, the declined member being adapted to deform to a relatively more level position under the weight of the wearer of the footwear and to return to its normal form on suspension of the weight.

CURRY ORA WALPER.
